(57) **ABSTRACT**

A liquid discharging head includes: a pressure chamber; a descender extending from the pressure chamber in a first direction; a communicating channel extending from the descender in a second direction crossing the first direction; a first return channel and a second return channel connecting the communicating channel and a return manifold; and a nozzle connected to the communicating channel. The first return channel and the second return channel are connected, with respect to the communicating channel, at facing positions, respectively, the facing positions facing each other in a direction orthogonal to the second direction; and the nozzle is provided, in the communicating channel, at a position which is offset from an axis of the descender, and which is sandwiched between a connecting location of the first return channel with respect to the communicating channel and a connecting location of the second return channel with respect to the communicating channel.

LIQUID DISCHARGING HEAD

CROSS REFERENCE TO RELATED APPLICATION

The present application claims priority from Japanese Patent Application No. 2019-204188, filed on Nov. 11, 2019, the disclosure of which is incorporated herein by reference in its entirety.

BACKGROUND

Field of the Invention

The present disclosure relates to a liquid discharging head.

Description of the Related Art

Conventionally, there is known a liquid discharging head including a nozzle, a pressure chamber, a nozzle communicating channel connected to the nozzle and the pressure chamber, and circulation individual channels each of which is connected to the nozzle communicating channel and a circulation common channel.

SUMMARY

In the above-described liquid discharging head, in a case that the liquid flows from the nozzle communicating channel to the circulation common channel, the liquid flows via the circulation individual channels. Therefore, the flow of the liquid is made uniform or uniformized in the nozzle communicating channel and the nozzle, and a path of the liquid discharged from the nozzle is prevented from deviating from a desired direction.

However, in the above-described liquid discharging head, the pressure applied to the pressure chamber is applied to the nozzle via the nozzle communicating channel. Accordingly, if the pressure is applied to the pressure chamber in a state that an air bubble enters from an opening of the nozzle (nozzle opening) into the nozzle, the air bubble is pushed to the nozzle by such pressure and remains in the nozzle. In this case, the nozzle opening might be blocked or closed by the air bubble, and/or the pressure might be absorbed by the air bubble adhered to a wall surface of the nozzle, and the liquid might not be discharged from the nozzle.

The present disclosure has been made to solve the above-mentioned problem, and an object of the present disclosure is to provide a liquid discharging head capable of suppressing an occurrence of any unsatisfactory discharge (defective discharge).

According to an aspect of the present disclosure, there is provided a liquid discharging head including: a pressure chamber; a descender extending from the pressure chamber in a first direction; a communicating channel extending from the descender in a second direction crossing the first direction; a first return channel and a second return channel connecting the communicating channel and a return manifold; and a nozzle connected to the communicating channel, wherein the first return channel and the second return channel are connected to the communicating channel, at facing positions, respectively, the facing positions facing each other in a direction orthogonal to the second direction; and the nozzle is provided, in the communicating channel, at a position which is offset from an axis of the descender and which is sandwiched between a connecting location of the

2

first return channel to the communicating channel and a connecting location of the second return channel to the communicating channel.

According to this configuration, since the liquid flows through the first and second return channels, the flow from the communicating channel to the return manifold is dispersed. Accordingly, in a nozzle provided at the position sandwiched between the connecting location of the first return channel to the communicating channel and the connecting location of the second return channel to the communicating channel, the flow of the liquid is made uniform, thereby making it possible to suppress any deviation, in the discharging direction of the liquid, with respect to the desired direction.

Further, the pressure applied to the pressure chamber changes the direction thereof from the first direction to the second direction as the pressure propagates to the communicating channel through the descender. Thus, even if any air bubble enters into the nozzle, a force pushing the air bubble into the nozzle is reduced. As a result, it is possible to suppress the occurrence of such a situation that the air bubble remains in the nozzle, and to suppress any unsatisfactory discharge such as discharge failure due to the air bubble, etc.

BRIEF DESCRIPTION OF THE DRAWINGS

FIG. 1 is a view schematically depicting a liquid discharging apparatus provided with a liquid discharging head according to an embodiment of the present disclosure.

FIG. 2 is a cross-sectional view of the liquid discharging head of FIG. 1, taken along a cross section orthogonal to a third direction.

FIG. 3 is a partial cross-sectional view of the liquid discharging head, taken along a line III-III of FIG. 2.

FIG. 4A is a partial cross-sectional view of a liquid discharging head according to a first modification; and FIG. 4B is a partial cross-sectional view of a liquid discharging head according to a second modification.

FIG. 5 is a partial cross-sectional view of a liquid discharging head according to a third modification.

DESCRIPTION OF THE EMBODIMENTS

In the following, an embodiment of the present disclosure will be described in detail, with reference to the drawings. Note that in the following description, same reference numerals are affixed to same or corresponding elements throughout all the drawings, and any overlapping explanation therefor will be omitted.

<Configuration of Liquid Discharging Apparatus>

A liquid discharging apparatus 11 is provided with a liquid discharging head (hereinafter referred to as a "head") 10 according to an embodiment of the present disclosure. The liquid discharging apparatus 11 is an apparatus which discharges or ejects a liquid such as an ink, etc., as depicted in FIG. 1. In the following, an explanation will be given about an example wherein the liquid discharging apparatus 11 is applied to an ink-jet printer which discharges or ejects a liquid with respect to a recording medium P so as to form an image. The liquid discharging apparatus 11, however, is not limited to this. Further, a sheet material such as paper, cloth, etc., can be used as the recording medium P.

The liquid discharging apparatus 11 adopts a line head system. The liquid discharging apparatus 11 is provided with: a platen 12, a conveying part 13, a head unit 14, a storing tank 15, and a controller 16. Note, however, that the

liquid discharging apparatus **11** is not limited to or restricted by the line head system, and the liquid discharging apparatus **11** may adopt another system such as a serial head system, etc.

The platen **12** is a flat plate member. The recording medium **P** is placed on the upper surface of the platen **12**.

The conveying part **13** has, for example, two conveying rollers **13a**, and a conveying motor. The two conveying rollers **13a** are arranged parallel to each other so as to sandwich the platen **12** therebetween in a conveyance direction. The two conveying rollers **13a** are connected to the conveying motor. In a case that the conveying motor is driven, the conveying rollers **13a** rotate and the recording medium **P** on the platen **12** is conveyed in the conveyance direction.

The head unit **14** extends to be long in a direction (orthogonal direction) orthogonal to the conveyance direction. In the orthogonal direction, the length of the head unit **14** is not less than the length of the recording medium **P**. The head unit **14** is provided with a plurality of pieces of the head **10**. Each of the heads **10** is provided with a discharge surface **21a** facing the upper surface of the platen **12**, and a plurality of nozzles holes **21b** which are open in the discharge surface **21a**. Note that the details of the head **10** will be described later on.

The storing tank **15** is provided as a plurality of storing tanks **15** for the kinds of the liquids, respectively. For example, four pieces of the storing tank **15** store black, yellow, cyan, and magenta liquids, respectively. Each of the liquids stored in one of the storing tanks **15** is supplied to the nozzle holes **21b** of one of the heads **10** corresponding to one of the storing tanks **15**, respectively. In a case that pressure is applied to the liquid inside a pressure chamber by a piezoelectric element, the liquid is discharged from the nozzle hole **21b**, as will be described later on.

The controller **16** includes a processor such as a CPU, a memory such as a RAM and ROM, etc., a driver IC such as a ASIC, etc. In a case that the CPU receives various requests and a detecting signal of a sensor, the CPU causes the RAM to store various kinds of data and outputs various execution commands or instructions to the ASIC, based on program(s) stored in the ROM. Based on the command, the ASIC controls respective driver ICs and executes an operation corresponding to the command. This drives the piezoelectric element of the head **10** and the conveying motor of the conveying part **13**.

For example, the controller **16** executes a discharging operation of discharging or ejecting the liquid from the nozzle holes **21a** of the head **10** and a conveying operation of conveying, by the conveying part **13**, the recording medium **P** in the conveying direction by a predetermined amount. With this, a printing processing of forming an image on the recording medium **P** is executed.

<Configuration of Head>

The head **10** includes a channel forming body **20**, and a volume changing part **30**, as depicted in FIGS. 2 and 3. A liquid channel is formed in the inside of the channel forming body **20**. The channel forming body **20** is constructed as a stacked body (laminated body) of a nozzle plate **21**, a first channel plate **22**, a second channel plate **23**, a third channel plate **24**, and a fourth channel plate **25**. These plates are stacked in a first direction in this order and are bonded to one another with an adhesive, etc.

Note that the number of the plates is not limited to this, and may be larger or smaller than this. In the following, a side on which the nozzle plate **21** is arranged with respect to the first channel plate **22** in the first direction is referred to

as a "lower side", and an opposite side thereto is referred to as an "upper side". However, the arrangement of the head **10** is not limited to this.

Each of the plates is flat plate-shaped, and each of the plates is formed with holes and grooves of various sizes. In the channel forming body **20** in which the plates are stacked, the holes and the grooves are combined to thereby form, for example, a plurality of nozzles **26**, a plurality of individual channels **40**, a supplying manifold **27** and a return manifold **28**, as the liquid channel.

The plurality of nozzles **26** penetrate through the nozzle plate **21** in the first direction. The plurality of nozzle holes **21b** are formed in the lower surface (discharge surface **21a**) of the nozzle plate **21**. A plurality of nozzle holes **21b** form a plurality of nozzle hole rows arranged side by side in a second direction. Each of the plurality of nozzle hole rows extends in a third direction.

Note that the second direction is a direction crossing the first direction (for example, a direction orthogonal to the first direction), and the third direction is a direction crossing the first direction and the second direction (for example, a direction orthogonal to the first direction and the second direction). Further, a direction in which the nozzle holes **21b** are aligned may be along the orthogonal direction of FIG. 1, or may be inclined with respect to the orthogonal direction. Further, a direction in which the nozzle hole rows are arranged side by side may be along the conveyance direction, or may be inclined with respect to the conveyance direction.

Each of the nozzles **26** has, in the first direction, a proximal end **26a** and a distal end **26b** which is on an opposite side to the proximal end **26a**. The nozzle hole **21b** is formed in the discharge surface **21a** by the distal end **26b** of the nozzle **26**. An axis **a1** of the nozzle **26** passes through the center of the proximal end **26a** and the center of the distal end **26b**, and extends in the first direction. The nozzle **26** has a tapered shape in which the cross-sectional area orthogonal to the axial direction (first direction) of the nozzle **26** is continuously reduced from the proximal end **26a** toward the distal end **26b**. The nozzle **26** has, for example, a conical shape such as a truncated conical shape, etc.

Each of the supply manifold **27** and the return manifold **28** is elongated or extends in the third direction and is connected to the plurality of individual channels **40**. The plurality of individual channels **40**, the return manifold **28** and the supply manifold **27** are arranged in this order in the second direction. Note that in the second direction, the side on which the supply manifold **27** is arranged with respect to the return manifold **28** is referred to as a "first side", and the side opposite to this side is referred to as a "second side". Further, the arrangement of the return manifold **28** and the supply manifold **27** is not limited to this. For example, the individual channel **40** may be arranged between the supply manifold **27** and the return manifold **28** in the second direction. Further, in the first direction, the supply manifold **27** may be stacked on the return manifold **28**.

A supply port is provided on the supply manifold **27**, at on one end in the longitudinal direction of the supply manifold **27**. A return port is provided on the return manifold **28**, at on one end in the longitudinal direction of the return manifold **28**. The supply port and the return port are connected to a sub tank provided in the head **10**. The sub tank is connected to one of the storing tanks **15** (FIG. 1) corresponding thereto, and the liquid is supplied from the storing tank **15** to the sub tank.

A cross-sectional area orthogonal to the third direction (third cross-sectional area) of the supply manifold **27**, and a

cross-sectional area orthogonal to the third direction (third cross-sectional area) of the return manifold **28** are same as each other. For example, a cross-sectional area orthogonal to the first direction (first cross-sectional area) of each of the supply manifold **27** and the return manifold **28** is in a range of not less than 0.01 mm^2 and not more than 0.05 mm^2 . A cross-sectional area orthogonal to the second direction (second cross-sectional area) of each of the supply manifold **27** and the return manifold **28** is in a range of not less than 0.1 mm^2 and not more than 0.5 mm^2 . The third cross-sectional area of each of the supply manifold **27** and the return manifold **28** is in a range of not less than 0.001 mm^2 and not more than 0.005 mm^2 . Each of the supply manifold **27** and the return manifold **28** is formed by through holes penetrating through the first channel plate **22** and the second channel plate **23** in the first direction. A lower end of each of the supply manifold **27** and the return manifold **28** is covered with the nozzle plate **21**, and an upper end of each of the supply manifold **27** and the return manifold **28** are covered with the third channel plates **24**.

The plurality of individual channels **40** branch from supply manifold **27** and are integrated into the return manifold **28**. The sub tank, the supply manifold **27**, the plurality of individual channels **40**, the return manifold **28** and the sub tank are connected in this order so as to construct a circulation path or circulation route. Note that the supply manifold **27** and the return manifold **28** may be connected to each other via a connecting channel. In such a case, the sub tank, the supply manifold **27**, the connecting channel, the return manifold **28** and the sub tank are connected in this order so as to form the circulation route.

In the following, although the construction of an individual channel **40** included in the plurality of individual channels **40** will be explained, the construction of remaining individual channels **40** included in the plurality of individual channels **40** are also same. An upstream end of the individual channel **40** is connected to the supply manifold **27**, and a downstream end of the individual channel **40** is connected to the return manifold **28**. Between the upstream end and downstream end of each of the plurality of individual channels **40**, the individual channel **40** is connected to the proximal end **26a** of the nozzle **26**. The individual channel **40** includes a supply channel **41**, a supply throttle **47**, a pressure chamber **42**, a descender **43**, a communicating channel **44** and a plurality of return channels (for example, a first return channel **45** and a second return channel **46**). The supply channel **41**, the supply throttle **47**, the pressure chamber **42**, the descender **43**, the communicating channel **44** and the plurality of return channels are arranged in this order.

The supply channel **41** penetrates through the third channel plates **24** in the first direction. A lower end of the supply channel **41** is connected to an upper end of the supply manifold **27**. The supply channel **41** extends upwardly in the first direction from the supply manifold **27**. The supply channel **41** is arranged closer to the first side than a central part in the second direction of the supply manifold **27**. A cross-sectional area orthogonal to the first direction (first cross-sectional area) of the supply channel **41** is smaller than the third cross-sectional area of the supply manifold **27**.

The supply throttle **47** is formed of a groove recessed from the lower surface of the fourth channel plate **25**. A lower end of the supply throttle **47** is covered by the third channel plate **24**. The supply throttle **47** extends in the second direction. A lower end on the first side of the supply throttle **47** is connected to an upper end of the supply channel **41**. A cross-sectional area orthogonal to the second

direction (second cross-sectional area) of the supply throttle **47** may be smaller than the third cross-sectional area of the supply manifold **27**, and may be not more than the first cross-sectional area of the supply channel **41**.

5 The pressure chamber **42** penetrates through the fourth channel plates **25** in the first direction. A lower end of the pressure chamber **42** is covered with the third channel plate **24**. The pressure chamber **42** extends in the second direction. An end on the first side of the pressure chamber **42** is 10 connected to an end on the second side of the supply throttle **47**. A cross-sectional area orthogonal to the second direction (second cross-sectional area) of the pressure chamber **42** is greater than the second cross-sectional area of the supply throttle **47**.

15 The descender **43** penetrates through the first channel plate **22** to the third channel plate **24** in the first direction. An upper end of the descender **43** is connected to a lower end on the second side of the pressure chamber **42**. The descender **43** extends downward in the first direction from 20 the pressure chamber **42**. A lower end of the descender **43** is covered by the nozzle plate **21**. A central axis (axis **a2**), of the descender **43**, which passes through the center of the upper end and center of the lower end of the descender **43** extends in the first direction. The descender **43** has a 25 columnar shape such as a cylindrical shape, etc. In the second direction, the return manifold **28** is arranged between the descender **43** and the supply manifold **27**.

30 The communicating channel **44** penetrates through the first channel plate **22** in the first direction. An upper end of the communicating channel **44** is covered with the second channel plate **23**, and a lower end of the communicating channel **44** is covered with the nozzle plate **21**. The communicating channel **44** has an end **44a** on the second side in the second direction, and an end **44b** on the first side in the 35 second direction. The end **44a** on the second side of the communicating channel **44** is connected to the first side of the descender **43**. The communicating channel **44** extends from the descender **43** toward the first side. A cross-sectional area (second cross-sectional area), of the communicating channel **44**, which is orthogonal to the second direction is 40 not more than the first cross-sectional area of the descender **43**.

45 A lower end of the communicating channel **44** is connected to the lower end of the descender **43**. Further, the proximal end **26a** of the nozzle **26** is connected to the lower end of the communicating channel **44**. As viewed along the first direction, the lower end of the descender **43** and the proximal end **26a** of the nozzle **26** do not overlap with each other. Namely, the nozzle **26** is provided in the communicating channel **44** at a position which is offset from the axis 50 **a2** of the descender **43**.

55 The center in the third direction of the communicating channel **44** is located at the center of the proximal end **26a** of the nozzle **26**. The center of the nozzle **26** is arranged on a central axis (axis **a3**) passing through the center of the end **44a** on the second side and the center of the end **44b** on the first side of the communicating channel **44**. Namely, the axis **a3** of the communicating channel **44** and the axis **a1** of the nozzle **26** cross each other. The nozzle **26** extends from the 60 communicating channel **44** toward the lower side in the first direction. A cross-sectional area orthogonal to the first direction (first cross-sectional area) of the nozzle **26** is smaller than the second cross-sectional area of the communicating channel **44**.

65 The first return channel **45** and the second return channel **46** penetrate through the first channel plate **22** in the first direction. An upper end of each of the first and second return

channels 45 and 46 is covered with the second channel plate 23, and a lower end of each of the first and second return channels 45 and 46 is covered with the nozzle plate 21. The first return channel 45 and the second return channel 46 connect the communicating channel 44 and the return manifold 28. Note that the details of the first return channel 45 and the second return channel 46 will be described later on.

The volume changing part 30 includes a vibration plate 31 and a piezoelectric element 32, and changes the volume of the liquid channel of the channel forming body 20. Note that the volume changing part 30 is not limited to that of the system using the piezoelectric element 32 (piezoelectric system); it is allowable that the volume changing part 30 may adopt, for example, a thermal system using a heating element or an electrostatic system using a conductive vibration plate and an electrode.

The vibration plate 31 is stacked on the fourth channel plate 25, and covers an upper end of the pressure chamber 42. Note that the vibration plate 31 may be integrally formed with the fourth channel plate 25. In such a case, the pressure chamber 42 is formed of a recessed part which is recessed upward in the first direction, from the lower surface of the fourth channel plate 25. In the fourth channel plate 25, an upper part, of the fourth channel plate 25, which is located above the pressure chamber 42 functions as the vibration plate 31.

The piezoelectric element 32 includes a common electrode 32a, a piezoelectric layer 32b and an individual electrode 32c. The common electrode 32a, the piezoelectric layer 32b and the individual electrode 32c are arranged in this order in the first direction. The common electrode 32a covers the entire surface of the vibration plate 31 via an insulating film. The piezoelectric layer 32b is provided for each of the pressure chamber 42, and is arranged on the common electrode 32a. The individual electrode 32c is provided for each of the pressure chamber 42, and is arranged on the piezoelectric layer 32b so as to overlap with the pressure chamber 42. One piece of the piezoelectric element 32 is constructed by one piece of the individual electrode 32c, the common electrode 32a, and a part or portion (active part), of the piezoelectric layer 32b, which is sandwiched by one piece of the individual electrode 32c and the common electrode 32a.

The individual electrode 32c is electrically connected to a driver IC. The driver IC receives a control signal from the controller 16 (FIG. 1) so as to generate a driving signal (voltage signal) and applies the driving signal to the individual electrode 32c. On the other hand, the common electrode 32a is constantly maintained at the ground potential.

Depending on the driving signal, the active part of the piezoelectric layer 32b expands or contracts in a plane direction, together with the two electrodes 32a and 32c. In response to this, the vibration plate 31 deforms in a direction for increasing or decreasing the volume of the pressure chamber 42. With this, a discharge pressure is applied to the liquid inside the pressure chamber 42 so as to discharge or eject the liquid from the nozzle 26.

<Flow of Liquid>

For example, the supply port of the supply manifold 27 and the sub tank are connected by a supply piping, and the return port of the manifold 28 and the sub tank are connected by a return piping. In a case that a pressure pump of the supply piping and a negative pressure pump of the return piping are driven, the liquid flows from the sub tank, flows

through the supply pipe, flows into the supply manifold 27, and flows through the supply manifold 27 in the third direction.

During this time, a part of the liquid flows into the plurality of individual channels 40. The liquid flows from the supply manifold 27 into the supply channel 41 of each of the plurality of individual channels 40; the liquid flows through the supply channel 41 in the first direction; the liquid flows through the supply throttle 47 in the second direction, and the liquid further flows through the pressure chamber 42 in the second direction. Then, the liquid flows in the descender 43 in the first direction, and flows in the communicating channel 44 in the second direction. Further, in the communicating channel 44, a part of the liquid flows into the nozzle 26 and flows from the proximal end 26a to the distal end 26b in the first direction. Here, in a case that the discharge pressure is applied to the liquid inside the pressure chamber 42 by the piezoelectric element 32, a pressure wave is propagated from the pressure chamber 42 to the nozzle 26 via the descender 43 and the communicating channel 44, thereby discharging or ejecting the liquid from the nozzle hole 21b.

Further, the remaining part of the liquid in the communicating channel 44 flows from the communicating channel 44 and into the first return channel 45 and the second return channel 46; and the remaining part of the liquid flows in the second direction through each of the first and second return channels 45, 46 and flows into the return manifold 28. Then, the liquid flows through the return manifold 28 in the third direction, flows through the return piping, and returns to the sub tank. In such a manner, the liquid which has not been discharged from the nozzle 26 circulates between the sub tank and the individual channel 40.

<Configuration of First Return Channel and Second Return Channel>

A lower end of each of the first return channel 45 and the second return channel 46 is connected to the lower end of the communicating channel 44. An upper end of each of the first return channel 45 and the second return channel 46 is connected to the upper end of the communicating channel 44. The size in the first direction (height h2) of each of the first return channel 45 and the second return channel 46 is same as the size in the first direction (height h1) of the communicating channel 44. Each of the height h1 and the height h2 is, for example, in a range of not less than 0.01 μm and not more than 0.05 μm . Thus, in the axial direction of the nozzle 26 (first direction), it is possible to make (secure) the height h1, of the channel (the communicating channel 44) which is located closer to the pressure chamber 42 than the nozzle 26, to be great. With this, it is possible to lower any reduction in a component in the first direction of the pressure propagated from the pressure chamber 42 to the communicating channel 44 via the descender 43. This pressure is applied from the communicating channel 44 to the nozzle 26 extending in the first direction, and the liquid is discharged from the nozzle 26. Therefore, it is possible to prevent the occurrence of non-discharge of the liquid and reduction in the discharge amount due to the insufficient pressure, and to suppress the occurrence of unsatisfactory discharge.

Further, each of the first return channel 45 and the second return channel 46 has the cross-sectional area orthogonal to the direction in which the liquid flows is smaller than the second cross-sectional area of the communicating channel 44 and the third cross-sectional area of the return manifold 28. Accordingly, it is possible to reduce the occurrence of such a situation that the pressure applied to the liquid inside the pressure chamber 42 escapes from the communicating

channel 44 to the return manifold 28 via each of the first and second return channels 45 and 46. Therefore, it is possible to suppress the occurrence of the unsatisfactory discharge.

The first return channel 45 has a first upstream end 45a in the direction in which the liquid flows, and a first downstream end 45b which is on the opposite side to the first upstream end 45a. The first upstream end 45a is connected to the first side of the communicating channel 44, and the first downstream end 45b is connected to the second side of the return manifold 28. The second return channel 46 has a second upstream end 46a in the direction in which the liquid flows, and a second downstream end 46b which is on the opposite side to the second upstream end 46a. The second upstream end 46a is connected to the first side of the communicating channel 44, and the second downstream end 46b is connected to the second side of the return manifold 28.

The first upstream end 45a of the first return channel 45 is connected to one side in the third direction of the communicating channel 44, and the second upstream end 46a of the second return channel 46 is connected to the other side in the third direction of the communicating channel 44. A length in the second direction from the descender 43 to the first upstream end 45a and a length in the second direction from the descender 43 to the second upstream end 46a are same as each other. The first upstream end 45a and the second upstream end 46a are opposed to each other (face each other) in the third direction, with the communicating channel 44 sandwiched therebetween. Namely, the first return channel 45 and the second return channel 46 are connected at facing positions which are in the communicating channel 44 and which face each other in the third direction.

The nozzle 26 is arranged between a connection location at which the first return channel 45 is connected to the communicating channel 44 and a connection location at which the second return channel 46 is connected to the communicating channel 44. In other words, the nozzle 26 is arranged between the first upstream end 45a of the first return channel 45 and the second upstream end 46a of the second return channel 46. In the second direction, a position of an end on the first side of the nozzle 26 is same as a position of an end on the first side of each of the first and second upstream ends 45a and 46a, is same as a position of an end on the second side of each of the first and second upstream ends 45a and 46a, or is a position between the end on the first side of each of the first and second upstream ends 45a and 46a and the end on the second side of each of the first and second upstream ends 45a and 46a. Alternatively, a position of an end on the second side of the nozzle 26 is same as the position of the end on the first side of each of the first and second upstream ends 45a and 46a, is same as the position of the end on the second side of each of the first and second upstream ends 45a and 46a, or is the position between the end on the first side of each of the first and second upstream ends 45a and 46a and the end on the second side of each of the first and second upstream ends 45a and 46a. Further, the nozzle 26 is provided, in the communicating channel 44, at a position which is offset from the axis a2 of the descender 43.

According to this, the liquid flows from the communicating channel 44 to the first return channel 45 and the second return channel 46, thereby dispersing the flow from the communicating channel 44 to the return manifold 28. Therefore, the flow of the liquid in the nozzle 26 is made to be uniform, thereby making it possible to suppress the occurrence of any deviation in the discharge direction of the liquid

with respect to the desired direction. Further, in a case that the pressure applied to the liquid inside the pressure chamber 42 propagates from the pressure chamber 42 to the communicating channel 44 via the descender 43, the pressure changes direction thereof from the first direction to the second direction. Accordingly, even if the any air bubble enters into the nozzle 26, a force of pushing the air bubbles to the nozzle 26 is reduced. As a result, it is possible to reduce such a situation that the air bubble remains in the nozzle 26, and to suppress any unsatisfactory discharge caused by the air bubble.

Here, the nozzle 26 has the tapered shape in which the cross-sectional area orthogonal to the axial direction is reduced from the proximal end 26a toward the distal end 26b. In the nozzle 26 having such a tapered shape with the reduced diameter, the air bubble is likely to remain in the nozzle 26. However, in the present embodiment, since the nozzle 26 is connected to the communicating channel 44, it is possible to reduce the remaining or stagnation of the air bubble in the nozzle 26.

The first upstream end 45a of the first return channel 45 and the second upstream end 46a of the second return channel 46 are connected to the end 44b on the first side of the communicating channel 44. Further, the second downstream end 45b of the first return channel 45 and the second downstream end 46b of the second return channel 46 are connected to the second side of the return manifold 28. Here, since the end on the first side of each of the first and second upstream ends 45 and 46 and the end 44b on the first side of the communicating channel 44 are joined, the first return channel 45 and the second return channel 46 continuously extend from the end 44b on the first side of the communicating channel 44, without any step or stepped part.

With this, the liquid flows from the end 44a on the second side to the end 44b on the first side of the communicating channel 44. The flow of the liquid makes contact with the end 44b on the first side, which in turn reduces a component in the second direction. Further, the flow of the liquid branches into the first return channel 45 and the second return channel 46 at the end 44b on the first side. Accordingly, in the flow of the liquid, a component toward the first return channel 45 (toward one side in the third direction) and a component toward the second return channel 46 (toward the other side in the third direction) cancel each other out. With this, the uniformity of the flow of the liquid is improved in the nozzle 26 sandwiched between the first return channel 45 and the second return channel 46, thereby making it possible to suppress any deviation in the discharge direction with respect to the desired direction.

The communicating channel 44 has a connecting location (first connection port 44c) with respect the first return channel 45, a connecting location (second connection port 44d) with respect to the second return channel 46, and a connecting location (third connection port 44e) with respect to the nozzle 26. The first upstream end 45a of the first return channel 45 is connected to the first connection port 44c, and the communicating channel 44 communicates with the first return channel 45. The second upstream end 46a of the second return channel 46 is connected to the second connection port 44d, and the communicating channel 44 communicates with the second return channel 46. The proximal end 26a of the nozzle 26 is connected to the third connection port 44e, and the communicating channel 44 communicates with the nozzle 26. A center 44ec of the third connection port 44e is on the axis a1 of the nozzle 26, and is arranged on a

11

line segment L connecting a center 44ec of the first connection port 44c and a center 44dc of the second connection port 44d.

According to this, in the flow of the liquid, a component from the communicating channel 44 toward one side in the third direction and a component from the communicating channel 44 toward the other side in the third direction cancel each other out on the line segment L. By arranging the center of the nozzle 26 at such a position, it is possible to further uniformize the flow of the liquid in the nozzle 26, thereby making it possible to further suppress the deviation in the discharge direction of the liquid from the nozzle 26.

Each of the first return channel 45 and the second return channel 46 is bent along a plane or surface orthogonal to the first direction. For example, the first return channel 45 has a first upstream part 45c which extends linearly from the first upstream end 45a to one side in the third direction, a first bent part 45d which is bent from the first upstream part 45c in the second direction, and a first downstream part 45e which extends linearly from the first bent part 45d to the first side in the second direction. Namely, the first return channel 45 is bent from the third direction to the second direction. The second return channel 46 has a second upstream part 46c which extends linearly from the second upstream end 46a to the other side in the third direction, a second bent part 46d which is bent in the second direction from the second upstream part 46c, and a second downstream part 46e extending linearly from the second bent part 46d to the first side in the second direction. Namely, the second return channel 46 is also bent from the third direction to the second direction.

According to this, it is possible to suppress any spread of each of the first and second return channels 45 and 46 in the second direction and the third direction, without shortening the length of each of the first return channel 45 and the second return channel 46. Thus, it is possible to suppress any increase in the size of the head 10, while suppressing the occurrence of unsatisfactory discharge which is caused due to such a situation that the pressure applied to the liquid inside the pressure chamber 42 escapes through the respective first and second return channels 45 and 46. Further, since the angle of each of the first and second bent parts 45d and 46d is 90 degrees, it is possible to easily form each of the first and second return channels 45 and 46.

The first return channel 45 and the second return channel 46 have shapes symmetrical with respect to the axis a3 of the communicating channel 44 extending in the second direction. For example, the first upstream part 45c and the second upstream part 46c extend, in the third direction, from the communicating channel 44 in mutually opposite sides, respectively. Further, the first upstream part 45c and the second upstream part 46c have lengths thereof in the third direction and cross-sectional areas thereof orthogonal to the third direction which are same as each other. The first downstream part 45e and the second downstream part 46e sandwich the communicating channel 44 therebetween and extend in the second direction. Furthermore, the first downstream part 45e and the second downstream part 46e have lengths thereof in the second direction and cross-sectional areas thereof orthogonal to the second direction which are same as each other. According to this, the flow amount of the liquid flowing from the communicating channel 44 to the first return channel 45 and the flow amount of the liquid flowing from the communicating channel 44 to the second return channel 46 are uniformized, thereby making it possible to uniformize the flow of the liquid in the nozzle 26, and to suppress the deviation in the discharging direction.

12

The channel resistance of the first return channel 45 and the channel resistance of the second return channel 46 are same as each other. For example, the cross-sectional area and the length of the first return channel 45 are same as the cross-sectional area and the length of the second return channel 46, respectively. The angles of the first upstream part 45c of the first return channel 45 and the second upstream part 46c of the second return channel 46 with respect to the communicating channel 44 are same as each other, and the angles of the first downstream part 45e of the first return channel 45 and the second downstream part 46e of the second return channel 46 with respect to the return manifold 28 are both 90 degrees. According to this, since the flow amount of the liquid flowing from the communicating channel 44 to the first return channel 45 and the flow amount of the liquid flowing from the communicating channel 44 to the second return channel 46 are uniformized, the flow of the liquid in the nozzle 26 is uniformized, thereby making it possible to suppress the deviation in the discharging direction. Note that in a case that the channel resistance of the first return channel 45 and the channel resistance of the second return channel 46 are same, it is allowable that the cross-sectional area, length, and angle with respect to the communicating channel 44 of the first return channel 45 are made different from the cross-sectional area, length, and angle with respect to the communicating channel 44 of the second return channel 46, respectively.

<First Modification>

In a head 10 according to a first modification, as depicted in FIG. 4A, a third connection port 144e is arranged on a line segment L connecting a center 44cc of a first connection port 44c and a center 44dc of a second connection port 44d. However, a center 144ec of the third connection port 144e is shifted from the line segment L in the second direction, and a gap is defined between the center 144ec and the line segment L. Note that other than this point, the third connection port 144e is similar to the third connection port 44e.

In the second direction, the line segment L is arranged between the center 144ec and the end on the second side of the third connection port 144e, or the line segment L is arranged between the center 144ec and the end on the first side of the third connection port 144e. Further, in the second direction, the center 144ec of the third connection port 144e may be on the first side relative to the line segment L, or may be on the second side relative to the line segment L. Even in such a case, in the flow of the liquid, a component from the communicating channel 44 toward the first return channel 45 and a component from the communicating channel 44 toward the second return channel 46 cancel each other out. With this, the flow of the liquid in the nozzle 26 is uniformized, thereby making it possible to suppress the deviation in the discharging direction.

<Second Modification>

In a head 10 according to a second modification, as depicted in FIG. 4B, a first return channel 145 and a second return channel 146 are connected to locations, of the communicating channel 44, which are closer to the second side in the second direction than the end 44b on the first side of the communicating channel 44. Note that other than this point, the first return channel 145 and the second return channel 146 are similar to the first return channel 45 and the second return channel 46, respectively.

The first return channel 145 and the second return channel 146 are connected, in the second direction, between an end 44b on the first side and an end 44a on the second side of the communicating channel 44. At an upstream end 145a of the first return channel 145, an end on the second side thereof in

the second direction is located on the first side with respect to the end 44a on the second side of the communicating channel 44, and an end on the first side thereof in the second direction is located on the second side with respect to the end 44b on the first side of the communicating channel 44. Similarly, at an upstream end 146a of the second return channel 146, an end on the second side thereof in the second direction is located on the first side with respect to the end 44a on the second side of the communicating channel 44, and an end on the first side thereof in the second direction is located on the second side with respect to the end 44b on the first side of the communicating channel 44. In other words, the communicating channel 44 extends from the first upstream side 145a and the second upstream side 146a to the second side and to the first side in the second direction. Even in this case, since the nozzle 26 is arranged at a position, in the communicating channel 44, which is sandwiched between the first upstream end 145a and the second upstream end 146a. Accordingly, it is possible to uniformize the flow of the liquid in the nozzle 26 while preventing the air bubble from remaining therein, and to suppress the occurrence of unsatisfactory discharge.

<Third Modification>

In a head 10 according to a third modification, as depicted in FIG. 5, each of a first return channel 245 and a second return channel 246 extend linearly. Note that other than this point, the first return channel 245 and the second return channel 246 are similar to the first return channel 45 and the second return channel 46, respectively.

For example, each of the first and second return channels 245 and 246 is arranged to be inclined with respect to the communicating channel 44 and the return manifold 28 along a plane or surface orthogonal to the first direction. The first and second return channels 245 and 246 extend linearly and obliquely with respect to the second and third directions from first and second upstream ends 245a, 246a thereof toward first and second downstream ends 245b, 246b, respectively, so that the distance in the third direction between the first and second return channels 245 and 246 is increased.

In a case that the first and second return channels 245 and 246 are bent, there is a possibility that the air bubble might be caught, for example, in a recessed corner part thereof, etc. In contrast, in a case that the first and second return channels 245 and 246 extend straight, since the air bubble flows smoothly from the communicating channel 44 through each of the first and second return channels 245 and 246 to be discharged, it is possible to suppress such a situation that the air bubble enters from the communicating channel 44 to the nozzle 26. Therefore, it is possible to suppress the unsatisfactory discharge due to the air bubble.

Note that in the first return channel 245 and the second return channel 246, the angles thereof with respect to the communicating channel 44 are same as each other. However, in the first return channel 245 and the second return channel 246, the angles thereof with respect to the return manifold 28 are different from each other. Accordingly, an angle defined by a direction in which the liquid flows in the first return channel 245 and a direction in which the liquid flows in the return manifold 28, and an angle defined by a direction in which the liquid flows in the second return channel 246 and the direction in which the liquid flows in the return manifold 28 are different from each other. Therefore, it is allowable that the shape of the first return channel 245 and the shape of the second return channel 246 may be different from each

other so that the channel resistance of the first return channel 245 and the channel resistance of the second return channel 246 are same as each other.

<Other Modifications>

5 In the above-described embodiment and the first and second modifications, each of the first and second return channels is bent, from the upstream end thereof to the downstream end thereof, from the third direction to the second direction at 90 degrees; the angle, however, is not limited to 90 degrees. For example, the angle of bending of each of the first and second return channels may be greater than 90 degrees. In such a case, since an angle at which each of the first and second return channels is recessed becomes large, the air bubble is less likely to remain in each of the first and second return channels. Therefore, it is possible to suppress the occurrence of unsatisfactory discharge caused by the air bubble, while suppressing the increase in the size of the head 10.

In the above-described embodiment and the first and 20 second modifications, each of the first and second return channels is bent in the second direction and the third direction; however, the shape in which each of the first and second return channels is bent is not limited to this. For example, each of the first and second return channels may be 25 curved. In such a case, a part or all of each of the first and second return channel may be curved. With this, since any corner part which is recessed is not formed in each of the first and second return channels, the air bubble is allowed to flow smoothly and is discharged. Therefore, it is possible to 30 reduce the occurrence of unsatisfactory discharge caused by the air bubble, while suppressing the increase in the size of the head 10.

In the above-described embodiment and each of the 35 modifications, although the nozzle 26 has the tapered shape, the shape of the nozzle 26 is not limited to this. For example, the nozzle 26 may be cylindrical shaped such that the area of the proximal end 26a of the nozzle 26 is same as the area of the distal end 26b of the nozzle 26.

The above-described embodiment and respective modifications 40 may be combined with each other as long as they are not mutually exclusive. For example, in the second and third modifications and the other modification(s), the third connection port may be arranged on the line segment L as in the first modification. In the third modification and the other modifications, each of the first and second return channels 45 may be connected, in the second direction, at a location closer to the second side of the communicating channel than the first end of the communicating channel, as in the second modification.

45 From the above-described explanation, numerous improvements and/or other embodiments of the present disclosure will be apparent to those skilled in the art. Accordingly, the foregoing explanation should be interpreted as a mere example, and as being provided for the purpose of providing, to those skilled in the art, the best mode for carrying out the present disclosure. The configuration and/or the detailed function of the present disclosure may be substantially changed, without departing from the spirit of the present disclosure.

50 What is claimed is:

1. A liquid discharging head comprising:
a pressure chamber;
a descender extending from the pressure chamber in a first direction;
a communicating channel extending from the descender in a second direction crossing the first direction;

15

a first return channel and a second return channel connecting the communicating channel and a return manifold; and

a nozzle connected to the communicating channel, wherein the first return channel and the second return channel are connected to the communicating channel at facing positions, respectively, the facing positions facing each other in a direction orthogonal to the second direction; and

the nozzle is provided, in the communicating channel, at a position which is offset from an axis of the descender, and which is sandwiched between a connecting location of the first return channel to the communicating channel and a connecting location of the second return channel to the communicating channel.

2. The liquid discharging head according to claim 1, wherein the communicating channel has one end connected to the descender and the other end on an opposite side to the one end, and

the first return channel and the second return channel are connected to the other end of the communicating channel.

3. The liquid discharging head according to claim 1, wherein the communicating channel has a first connection port connected to the first return channel, a second connection port connected to the second return channel, and a third connection port connected to the nozzle, and the third connection port is arranged on a line segment connecting a center of the first connection port and a center of the second connection port.

16

4. The liquid discharging head according to claim 3, wherein a center of the third connection port is arranged on the line segment.

5. The liquid discharging head according to claim 1, wherein channel resistance of the first return channel and channel resistance of the second return channel are same as each other.

10 6. The liquid discharging head according to claim 1, wherein the first return channel and the second return channel have shapes which are symmetric with respect to an axis, of the communicating channel, extending in the second direction.

15 7. The liquid discharging head according to claim 1, wherein each of the first return channel and the second return channel is bent in a direction orthogonal to the first direction.

8. The liquid discharging head according to claim 1, wherein each of the first return channel and the second return channel extends straight.

20 9. The liquid discharging head according to claim 1, wherein the nozzle has a proximal end connected to the communicating channel, and a distal end located on an opposite side to the proximal end, and the nozzle has a tapered shape in which a cross-sectional area orthogonal to an axial direction of the nozzle is reduced from the proximal end toward the distal end.

25 10. The liquid discharging head according to claim 1, wherein in an axial direction of the nozzle, a size of the communicating channel is same as a size of the first return channel and same as a size of the second return channel.

* * * * *
